UNITED STATES PATENT OFFICE

2,475,349

MOWING MACHINE GUARD

Martin Boyer, Lowry, Minn., assignor of one-fourth to Birth A. McIver, Lowry, Minn.

Application December 8, 1945, Serial No. 633,736

1 Claim. (Cl. 56—309)

1

The invention as described herein, and illustrated in the accompanying drawings, consists of a rivetless ledger plate, an object of which is to provide means whereby the plate may be secured to the guard finger without the use of rivets.

Another object of the invention is to provide a ledger plate and a spring pull back therefor.

A further object of this invention is to provide a guard in the rear part of which is provided a rivet with a protruding head, an end of a pull spring attached to the head, and a ledger plate to the outer end of which is removably attached the other end of the spring whereby the plate is detachably held in place.

Other features and advantages will become more readily apparent from the following description and the accompanying illustrative drawings in which:

Figure 1 is a plan view of my device,

Figure 2 is a sectional view on line 2—2 of Figure 1, and

Figure 3 is a detail plan view of a ledger plate.

While one embodiment of my invention is illustrated in the above referred to drawings, it is to be understood that they are merely for the purpose of illustration and that various changes in construction may be resorted to in the course of manufacture in order that the invention may be utilized to the best advantage according to circumstances which may arise, without in any way departing from the spirit and intention of my device, which is to be limited only in accordance with the appended claim. And while I have stated the primary field of utility of my invention it remains obvious that it may be employed in any other capacity wherein it may be found applicable.

In the accompanying drawings, and in the following specification, the same reference characters are used to designate the same parts and elements throughout and in which 10, refers to the invention and 11, indicates a guard for mowing machines and the like in the rear or heel portion 12, of which is provided a vertical bore 13, the lower end 14, of which is enlarged and flared to provide for the like shaped lower end 15, of a rivet 16, the head 17, of which projects above the surface of the wall 18, for engagement with the eye 19, on the terminal end 20, of a pull spring 21, which terminates in an elongated shank 22, the terminal of which is returned to form a hook 23, engageable in the notch 24, of the outer end 25, of a ledger plate 26, the rear end 27, is provided with inwardly inclined ends 28 and 29, to fit the recess 30, on

2

the said guard member 12. The extreme inner end 31, of the plate 26, is provided with a cut out 32, and against which and within which said recess 30, the ledger plate is securely held through the action of spring 21. The outer end 25, of the plate 26, and the hook 23, seat within the recess 34, in the point end 35, of the guard 12. To remove the ledger plate it becomes necessary only to project the point of a nail into said cut out 32, and prise the rear end of the plate up above the surface of the guard 12 whereupon the action of the spring 21, will cause the plate to leap from the guard.

It is thought that persons skilled in the art to which the invention relates will be able to obtain a clear understanding of the invention after considering the description in connection with the drawings. Therefore, a more lengthy description is regarded as unnecessary.

Changes in shape, size and rearrangement of details and parts such as come within the purview of the invention claimed may be resorted to, in actual practice, if desired.

Having now described the invention that which is claimed to be new and desired to be procured by Letters Patent is:

In a mowing machine, a guard finger, a ledger plate seat on said finger having rearwardly converging side walls, a ledger plate on said seat having converging side walls engaging the side walls of the seat, the seat having a recess opening through its top face between the convergent ends of the side walls, the ledger plate having a notch opening through its end between the convergent ends of the side walls thereof through which an instrument may be introduced into the recess and beneath the ledger plate to lift the rear end of the ledger plate off of the seat, a retractile coil spring anchored at one end to the finger beneath the ledger plate and a hook on the opposite end of the spring for engaging the end of the ledger plate remote from the seat yieldingly to hold the convergent side walls of the ledger plate against the convergent side walls of the seat.
